UNITED STATES PATENT OFFICE

2,039,101

ELECTRIC DISCHARGE DEVICE AND CON-
TROL APPARATUS THEREFORElmer D. McArthur, Schenectady, N. Y., assignor
to General Electric Company, a corporation of
New York

Application April 28, 1934, Serial No. 722,918

14 Claims. (Cl. 250—27)

The present invention relates to electric discharge apparatus and more particularly to thermionic devices containing a cathode and an anode and having a discharge of an arc or glow form passing between the electrodes. In devices of this sort, an ionizable medium is generally employed, such as mercury vapor or inert gas, the purpose of which during operation is to neutralize space charge and to permit cumulative ionization. Tubes of this character are capable of handling relatively large amounts of current, since the voltage losses are reduced to a minimum.

In order to control this large amount of power, it is usual to employ an electrostatic control member or grid positioned between the cathode and anode. The function of the grid is to control the initiation of the arc and when alternating voltage is impressed between the cathode and anode, the grid ordinarily triggers the tube at the same point in each positive half-cycle of the voltage in order that the average current over succeeding periods of time may be constant. However, when electrostatic control members are employed in tubes of this character, particularly those having unusual electrode design or when operating under exaggerated conditions, certain difficulties may attend the use of such a member. For example, the grid may become an emitter of electrons, or when voltage transients are set up in the circuits associated with the tube, these transients may be transferred by inductive electrostatic effect to the grid and thereby reduce its control function. In order to eliminate some of these difficulties, it has been proposed to move the control member, from within the tube to a position on the exterior thereof but in this case, other difficulties have been found which limit to a certain extent the field of usefulness of such devices.

In accordance with the present invention, I provide an entirely novel form of control in devices of this character, a control which does not require the usual form of control electrode, i. e. an electrostatic control member, either within or without the device, and yet one which is practical and effective.

An object of my invention, therefore, is to provide a novel form of control for tubes of the arc or glow type, one which eliminates the necessity for the usual electrostatic control member, and yet, provides a powerful control effect for accurately determining when the arc shall start during the recurring positive half-cycles of the applied anode alternating voltage. A further object is to simplify the construction and design of

controlled arc or glow discharge devices. In carrying out these objects, the invention contemplates the use of a magnetic field which is so positioned with respect to the tube as to affect the direction of movement of the electrons which normally pass to the anode and which cause initiation of the arc or glow. The effect of the magnetic field is to reduce but preferably entirely to prevent ionizing collisions between the electrons emitted by the cathode and gas or vapor molecules of the ionizable medium within the envelope.

The invention will be better understood when reference is made to the following description and accompanying drawings in which Fig. 1 is a view, partly in diagram and partly in section, of an arc discharge tube and an associated magnet system for controlling initiation of the arc; Fig. 2 is a diagram showing the equipotential lines in the tube illustrated in Fig. 1; Figs. 3 and 4 are diagrams of certain control characteristics of the apparatus shown in Fig. 1; Fig. 5 illustrates a modified form of tube employed with a magnetic field similar to that shown in Fig. 1; while Figs. 6 and 7 depict certain control characteristics of the apparatus illustrated in Fig. 5.

Referring more particularly to Figs. 1 and 2, numeral 1 designates an envelope of vitreous material which is provided at the top, as shown, with a metal terminal member 2 and at the bottom, 30 with a metal base 3 carrying a plurality of terminal pins 4 insulated from one another. The envelope is provided on the interior with a re-entrant stem and press 5 and contains a cathode 6, an anode 7 and an electrode 8, the purpose of 35 which will be explained hereinafter. The cathode 6 may be of the conventional indirectly heated type and consist of an outer cylindrical member and an inner cylinder 9 secured to the outer cylinder by vanes 10. The recesses formed between the cylinders and the vanes may be coated with electronically active material. The inner cylinder 9 is secured at one end to the cylinder 11. A cathode of this type is shown and claimed in the Hull and Ruggles Patent No. 1,924,318, granted August 29, 1933.

The cathode is preferably supported from the press by a pair of rigid leading-in conductors 12 which carry the load current, also the current 50 to the heater 11. The return conductor for the heater current is constituted of a leading-in wire 13 sealed in the press.

The anode 7 is mounted preferably at the opposite end of the envelope from the cathode and 55

may be constituted of an inverted dish-shaped metal member secured in place by the equidistantly spaced wires 14 and the central wire 15 which carries a pant-leg 16. The wire 15 is extended through the glass envelope to connect with the terminal 2.

The cylindrical member 8 which surrounds the anode and cathode is provided with a transverse metal web 18 having a central opening 19. The cylinder is mounted in place by means of a plurality of equidistantly spaced rods 20 secured to a screw clamp member 21 which surrounds the reentrant stem. Electrical connections are taken from the electrode 8, or rather, from the clamp 21, to one of the contact pins 4. There are also connections between the cathode 6 and one of the pins 4, and between the heater 11 and another of the pins.

The envelope contains an ionizable medium which may consist of inert gas, such as argon, at a pressure of from 50 to 800 microns, or vapor, such as caesium, or mercury.

Alternating voltage may be applied between the anode 7 and the cathode 6 by means of an alternator 22 through an adjustable step-up transformer 23. The heater 11 may be supplied with energy from a battery 24. It is sometimes desirable to maintain the electrode 8 at a different potential than the cathode and as shown, there is provided a battery 25 and a potentiometer 26, the battery being preferably so poled as to apply a negative charge on the electrode, the voltage of which may be indicated by a meter 27. When a tube and system, such as described, are operated, an arc or glow is formed between the cathode and anode during each recurring positive half-cycle of the anode voltage, provided the negative bias on the electrode 8 is not too large.

In accordance with the present invention, I propose to control the average amount of current flowing through the tube under these conditions, which control cooperates with the normally biased electrode 8 to determine precisely the point in each positive half-cycle of anode voltage at which the arc will start. For this purpose, there is provided a magnetic field which intercepts the space between the upper end of the cathode 6 and the transverse member or partition 18 of the electrode 8, the field being so directed as to pass through the tube in a direction normal to its longitudinal axis. The magnetic field may be obtained from a permanent magnet, but I prefer to employ an electromagnet which may consist of a U-shaped laminated core 29, with pole pieces directed toward the tube as shown, and having wound on one of its legs, a coil 31 in series with a battery 32 which may be poled in either direction as indicated, and a variable resistance 33.

When a magnetic field obtained in this manner is directed across the tube, the point in each positive half-cycle of anode voltage at which the tube is triggered may be positively controlled by the magnetic field, hence by the current flowing through the coil 31. In general, the stronger the field, the longer will the arc be restrained in each positive half-cycle and the later in the half-cycle will the arc be initiated.

While I do not wish to be limited to any theory, the operation of the tube under these conditions appears to depend upon the deflection of the electrons emitted by the cathode out of their normally straight path which would take them through the aperture 19 to the anode 7. There is an electric field extending in substantially

straight lines between these electrodes due to the voltage applied by the alternator 20. It is well known that electrons moving in an electric field which is normal to a magnetic field do not follow the direction of the electric field. The average direction of the motion of the electron is inclined away from the direction of the electric field by an angle θ which may be calculated from the following equation:

$$\tan \theta = \frac{He}{MV}$$

where

H is the magnetic field density,

e is the charge of the electron,

M is the mass of the electron,

V is the velocity of the electron,

λ is the mean free path of the electron among the gas molecules.

This relation shows that for a constant gas pressure, the field H required to produce any desired angular deflection depends on the velocity of the electrons. The less the velocity of electrons, the less will be the necessary field to produce the required angular deflection. By referring to the diagram in Fig. 2 which shows the electrical conditions in terms of equipotential lines, obtaining in a tube immediately prior to the initiation of an arc discharge, it will be noted that the volume bounded by the transverse member 18, cylindrical member 8 and the cathode 6 is an extremely low potential region. The potential distribution lines indicate that practically all of the voltage drop in the tube is confined to the space between the transverse member 18 and anode 7. It will of course be understood that the potential distribution lines are not absolutely accurate but only relatively so, because the plot does not include the effects principally due to positive ion space charges in the region between the anode and transverse member 18. Electrons cannot attain high velocities in the space between the cathode and member 18 and their paths, therefore, can be deflected through large angles with relatively weak magnetic fields. This figure also shows that electrons which normally would go through the opening in the baffle 18 to the anode can be deflected by a transverse magnetic field into a region where the electric and magnetic fields will return them to the cathode. When the potential of the electrode 8 and its baffle is only slightly negative or a few volts positive with respect to the cathode, many deflected electrons are probably collected by the electrode and to that extent, the latter serves as a barrier to the electrons. If, however, the electrode 8 is made several volts negative, the electrons will return directly to the cathode. In either case, the electron current flowing into the region between the anode and baffle 18 is reduced and the breakdown voltage increased. The term "breakdown voltage" is intended to mean the amount of anode voltage necessary to cause initiation of an arc or glow discharge for a given set of electrical conditions within the tube.

Consequently, when magnetomotive force is produced in the core 29 by the coil 31, the magnetic field, which preferably intercepts the space between the upper end of the cathode 6 and the baffle 18, tends to deflect the electrons which may either be collected by the electrode 8 or returned to the cathode, depending upon the polarity and magnitude of the bias given to the electrode. This bias of course may be delicately controlled by the potentiometer 26. By vary-

ing the amount of resistance 33 in the coil circuit and the amount and polarity of the bias, it is apparent that the magnetic field cooperates with the deflecting chamber contained within the electrode 8 to determine how many of the electrons pass through the opening 19 to reach the anode. The smaller the number of electrons which get through the opening 19 , the less is the likelihood of producing cumulative ionization within the device.

It will be noted that the cylindrical portion of the electrode 8 serves as a shield to protect the discharge path from electrical charges on the interior of the envelope. If this shielding were not present, electrons leaving the cathode might still be deflected toward the walls of the envelope but they would be reflected by the negative charge built up on the glass. These electrons would then follow along the walls toward the anode and eventually reach the latter. This condition of course would detract from the control effects of the magnetic field operating in conjunction with the deflection chamber so that in order to raise the breakdown voltage of the tube, it would be necessary to increase the strength of the magnetic field.

The general requirements of a tube design in which a magnetic field may be satisfactorily employed for controlling the initiation of an arc or glow discharge are:

1. A relatively large volume for a deflecting chamber.
2. Sufficient shielding so that the electric field in the chamber is low.
3. Conducting walls for the chamber.
4. A chamber partially bounded by the cathode.

The term "deflecting chamber", as referred to in the requirements noted immediately above, is intended to mean the space contained between the upper edge of the cathode and the lower surface of the transverse member or baffle 18 and bounded circumferentially by the cylindrical electrode 8 .

When the above conditions are met in a substantial degree, it has been found that practically all tubes of the electrostatically controlled arc discharge type which have heretofore been provided with an electrostatic control or grid member, can be successfully controlled by relatively weak transverse fields, provided the electrode within the tube which provides the deflection chamber is given the proper bias, depending upon the shape, size and position of the electrode with respect to the other electrodes.

Figs. 3 and 4 show certain operating characteristics of the typical tube and magnetic field shown in Fig. 1. In Fig. 3, curves are plotted for different strengths of magnetic field immediately preceding the breakdown of a tube or the initiation of an arc, with anode potential in volts as ordinate, and the potential of the electrode 8 in volts as abscissa. Taking a typical curve, for example, the 20 gauss curve, it will be noted that when a potential of approximately -3 volts is applied to the electrode 8 , the maximum anode voltage which may be applied to the tube before breakdown, is approximately 275 volts. When the magnetic field is increased to approximately 40 gauss as shown on the uppermost curve in this figure, and assuming the same potential on the electrode 8 (-3 volts), the breakdown anode voltage is raised to 700.

Fig. 4 shows the effect of changes in the tem-

perature of the condensate in a tube employing mercury vapor on the field strength and anode potential to cause breakdown of the tube. Taking an ordinary condensate temperature of approximately 40° C. and assuming that a maximum potential of 650 volts is applied to the anode, a magnetic field of approximately 35 volts will prevent a tube having the characteristics shown in this figure from breaking down and causing initiation of an arc or glow discharge through the mercury vapor.

Fig. 5 shows a construction of tube which is designed to operate more efficiently in connection with a transverse magnetic field than the tube shown in Fig. 1. It is apparent that in the tube illustrated in Fig. 1, there is considerable magnetic reluctance or resistance offered by the spaces contained between the cylinder 8 and each pole piece, and this magnetic resistance represents a loss which must be compensated for by a stronger magnetic field. Consequently, in the tube shown in Fig. 5, there is provided a pair of vanes 35 , of magnetic material, which extend from the inner surface of the envelope, adjacent the position of the pole pieces to a position which abuts the cathode cylinder 36 . The cylinder 36 is of longer length than the corresponding cylinder 6 shown in Fig. 1, because it has been extended beyond the interior vanes 37 which are indicated by the dotted lines, to form an electron-deflecting chamber of relatively large volume at the upper end of the cathode. The vanes 35 are provided with arcuate flanges at their outer ends which fit snugly against the inner wall of the envelope, and at their inner ends are secured directly to the cylinder 36 .

The vanes 35 may help to support a cylindrical member 52 , open at the top but closed at the bottom by a transverse member or baffle 38 which is provided with a central opening 39 . The cylinder 52 extends upwardly, preferably as far as or beyond the rear surface of the anode 40 . The anode may be mounted within the envelope in a similar manner to that described in connection with Fig. 1. The cylinder 52 is also supported from the combined stem and press 41 of the tube by means of several equidistantly spaced rods 42 which terminate at their lower ends in a screw clamp 43 , which fits tightly over the stem.

The cathode 36 which preferably is of the indirectly heated type, similar to that described in connection with Figs. 1 and 2, may be heated by a centrally positioned heater 44 energized by a battery 45 .

The envelope may contain mercury or other vapor, or inert gas, at a pressure sufficient to support an arc-like or glow discharge at the impressed voltages.

The magnetic field is provided by a core 46 , magnetically energized by a coil 47 , a battery 48 and a variable resistance 49 . Voltage may be applied between the anode 40 and the cathode 36 by means of an alternator 50 through an adjustable step-up transformer 51 . It will be noted that there is no biasing battery and potentiometer similar to that shown in Fig. 1 for the reason that the cylinder 52 is metallically connected to the cathode, hence is maintained at cathode potential.

As in the case of the apparatus shown in Fig. 1, the tube shown in Fig. 5 lends itself readily to the control by magnetic effects of the initiation of the arc or glow discharge. Thus the relation between the voltage necessary to cause break-

down and the strength of the magnetic field which is opposing the effect of the breakdown voltage is depicted in Fig. 6 by a plot drawn against plate voltage at breakdown as ordinate and field density in gausses as abscissa. When a field strength of approximately 26 gausses, for example, is applied to the deflection chamber contained within the upper end of the cylinder 36, it takes an anode voltage of approximately 560 10 to break the tube down. Lower intensities of field strength permit the arc or glow to be initiated by lower anode voltages.

In Fig. 7, the relation between the average current output of a tube of this type and the field strength is shown. It will be noted that a positive control of this current is effected by a relatively weak magnetic field between current values of from 1 to 2 amperes. Presumably, and as indicated in this figure, as the field strength rises 20 beyond 37 gausses, no current is permitted to flow through the tube so that at this point, a complete cut-off of the current is effected.

It will be noted that the vanes 35 materially aid in conducting the magnetic field through 25 the tube without appreciable loss at the position, i. e. within the deflection chamber, where it is used to deflect the electrons. The electrons which are deflected by the magnetic field of course return conductively to the cathode and hence, cannot 30 not build up any deleterious electric charge on any of the conducting members within the tube.

The McArthur application Serial No. 722,917, filed April 28, 1934 and entitled "Electric discharge devices," assigned to the same assignee 35 as the present invention, discloses and claims the adaptation of the magnetic method of controlling the initiation of the arc or glow discharge to a tube in which the electrons move radially or sideways from a cathode to a surrounding or adjacent anode.

The McArthur application Serial No. 722,919, filed April 28, 1934 and entitled "Control systems for gaseous discharge device," assigned to the same assignee as the present invention, discloses 45 and claims the feature of introducing a phase relation between the current energizing the arc or glow discharge device and the magnetomotive force of the magnetic control apparatus.

What I claim as new and desire to secure by 50 Letters Patent of the United States, is:

1. In combination, an electron discharge device comprising an envelope containing a source of electrons, an electron-receiving member, and an electrode mounted therebetween, a source of electromotive force connected between the electron source and the electron-receiving member, said electrode having such a configuration and being electrically charged so as to provide an electrostatic field of low intensity in the region of said 55 electron source, an ionizable medium in said envelope at a pressure under operating conditions sufficient to support an arc-like discharge, means for producing a magnetic field which intercepts the direction of said discharge in the region of said low intensity electrostatic field, said magnetic field having a maximum strength sufficient to prevent initiation of the discharge, means for controlling the strength of the magnetic field whereby initiation of the discharge and 60 the current flowing through the device are controlled.

2. In combination, an electron discharge device comprising an envelope containing a cathode, an anode and an electrode mounted therebetween, 75 a source of electromotive force connected be-

tween the cathode and anode, said electrode having such a configuration and being adapted to be charged negatively with respect to the cathode so as to provide an electrostatic field of low intensity in the region of said cathode, 5 an ionizable medium in said envelope at a pressure under operating conditions sufficient to support an arc-like discharge, means for producing a magnetic field which intercepts the direction of said discharge, said magnetic field being sufficiently strong to prevent initiation of the discharge when said electrode is charged negatively, and means for controlling the amount of negative charge on said electrode whereby the initiation of the discharge is controlled. 10 15

3. In combination, an electron discharge device comprising an envelope containing a cathode, an anode and an electrode mounted therebetween, a source of electromotive force connected between the cathode and anode, said electrode having such a configuration and adapted to be charged negatively with respect to the cathode, so as to provide an electrostatic field of low intensity in the region of said cathode, an ionizable medium in said envelope at a pressure under operating conditions sufficient to support an arc-like discharge, means for producing a magnetic field which intercepts the direction of said discharge, said magnetic field being sufficiently strong to prevent initiation of the discharge, and means for controlling the strength of the field and the amount of the negative charge on said electrode whereby the initiation of the discharge is controlled. 20 25 30

4. In combination, an electron discharge device comprising an envelope containing a cathode, an anode, and an electrode mounted therebetween, a source of alternating electromotive force connected between the cathode and anode, said electrode having such a configuration and being charged so as to provide an electrostatic field of low intensity in the region of said cathode, an ionizable medium in said envelope having a pressure under operating conditions sufficient to support an arc-like discharge, means for mounting exteriorly of the envelope for producing a magnetic field in a direction normal to the direction of said discharge, said magnetic field having a maximum strength sufficient to prevent initiation of the discharge during positive 50 half-cycles of the voltage impressed between the cathode and anode, and means for controlling the strength of the magnetic field whereby initiation of the discharge and the average value 55 of the current through the device are controlled.

5. In combination, an electron discharge device comprising an envelope containing a cathode, an anode, and an electron-deflecting chamber positioned between the cathode and anode, said chamber being substantially closed except for a discharge opening, a source of electromotive force connected between the cathode and anode, an ionizable medium in said envelope having a pressure under operating conditions sufficient to support an arc-like discharge, means mounted exteriorly of the envelope for causing the electrons in the deflection chamber to be deflected away from said opening, said means including a magnetic field of sufficient strength to restrain current from flowing through the opening, and means for varying the strength of the field whereby initiation of the discharge is controlled. 60 65 70

6. In combination, an electron discharge device comprising an envelope containing a cathode, an anode, and an electron-deflecting cham- 75

- ber positioned between the cathode and anode, said chamber being substantially closed except for a discharge opening in line with the cathode and anode, a source of electromotive force connected between the cathode and anode, an ionizable medium in said envelope having a pressure under operating conditions sufficient to support an arc-like discharge, means mounted exteriorly of the envelope for causing the electrons in the 5 deflection chamber to be deflected away from said opening whereby the number of electrons reaching the anode will be less than required to produce sufficient cumulative ionization to initiate a discharge within the device, said means 10 including a magnetic field of sufficient strength to restrain current from flowing through the opening, and means for varying the strength of the field whereby initiation of the discharge is controlled.
- 15 7. In combination, an electron discharge device comprising an envelope containing a cathode, an anode and an electrode, said electrode including a cylindrical portion surrounding the cathode and anode, and a transverse portion 20 mounted between the cathode and anode, sources of electromotive force connected respectively between the cathode and anode, and between the cathode and said electrode, an ionizable medium in said envelope having a pressure under operating conditions sufficient to support an arc-like 25 discharge, means mounted exteriorly of the envelope for producing a magnetic field in a direction normal to the direction of said discharge and in an area bounded by the cathode and the 30 transverse portion of said electrode, said field having a maximum strength sufficient to prevent initiation of the discharge when said electrode is biased negatively with respect to the cathode, and means for controlling the strength of the 35 field whereby the initiation of the discharge and the current through the device are controlled.
- 40 8. In combination, an electron discharge device comprising an envelope containing a cathode, an anode and a third electrode, said third electrode including a cylindrical portion surrounding the cathode and anode, and a transverse portion mounted between the cathode and anode, sources of electromotive force connected 45 respectively between the cathode and anode, and between the cathode and said third electrode, an ionizable medium in said envelope having a pressure under operating conditions sufficient to support an arc-like discharge, means mounted exteriorly of the envelope for producing a magnetic field in a direction normal to the direction of said discharge and in an area bounded by the cathode and the transverse portion of said third electrode, said field having a maximum strength 50 sufficient to prevent initiation of the discharge when said third electrode is biased negatively with respect to the cathode, and means for controlling the strength of the field and the amount of negative charge on said third electrode whereby initiation of the discharge and the current 55 through the device are controlled.
- 60 9. In combination, an electron discharge device comprising an envelope containing a cathode, an anode, a shield surrounding the anode and a pair of members of magnetic material secured to opposite sides of the cathode and extending toward the envelope, said shield secured to said members whereby the shield is maintained at cathode potential, a source of electromotive force connected between the cathode and anode, an ionizable medium in said envelope at 65
- 10 a pressure under operating conditions sufficient to support an arc-like discharge, a magnet mounted exteriorly of the envelope and having opposite poles arranged on opposite sides of the envelope, in line with said members of magnetic material, the field of said magnet having a maximum strength sufficient to prevent initiation of the discharge, and means for controlling the strength of the field whereby the initiation of the discharge and the current through the device are controlled.
- 15 10. An electron discharge device comprising an envelope containing a cathode, an anode, a cylindrical member surrounding the anode and provided with a restricted discharge opening, strips of magnetic material secured to opposite sides of the cathode and extending toward the envelope, said member being secured to said strips, an ionizable medium in said envelope at a pressure under operating conditions sufficient to support an arc- 20
- 25 11. In combination, an electron discharge device comprising an envelope containing a cathode, an anode, a cylindrical member interposed between the cathode and anode, said member being provided with a transverse baffle having a discharge opening therein, strips of magnetic material secured to opposite sides of the cathode and extending toward the envelope, said member being secured to said strips, an ionizable medium in said envelope at a pressure under operating conditions sufficient to support an arc-like discharge, and a magnet mounted exteriorly of the envelope and having pole pieces positioned in line with said strips.
- 30 35 12. In combination, an electron discharge device comprising an envelope containing a source of electrons, an anode, a hollow electrode interposed between said source and said anode and provided with a transverse web having a discharge opening therein, strips of magnetic material secured to opposite sides of said electron source and extending toward the envelope, said hollow electrode being secured to said strips, an ionizable medium in said envelope at a pressure under operating conditions sufficient to support an arc-like discharge, a source of alternating electromotive force connected between the anode and cathode, magnetic pole pieces mounted exteriorly of the envelope in line with said strips, and means for controlling the magnetic field passing through said pole pieces into said strips whereby the number of electrons emitted by said electron source and flowing through said discharge opening is controlled and the arc is restrained during a predetermined portion of the positive half-cycle of the anode voltage.
- 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

14. In the art of controlling the initiation of an arc-like discharge in an envelope containing an electron-emitting cathode, an anode, an interposed electrode adapted to serve as a barrier for electrons which move in curved paths and providing a region wherein the electrostatic field is of relatively low intensity, and an ionizable medium at a pressure under operating conditions sufficient to support an arc-like discharge, the

method which consists in magnetically deflecting the electrons at a position between the cathode and said electrode where the electrostatic field is of relatively low intensity whereby the electrons are moved out of their normal rectilinear paths to such an extent that the electrons are intercepted by said interposed electrode and the formation of an arc is restrained. 5

ELMER D. McARTHUR.
